DESIGN FOR A SLIDE FASTENER CLOSURE

Ralph Kay, New York, N. Y.

Application April 19, 1939, Serial No. 84,376

Term of patent 3½ years

To all whom it may concern:

Be it known that I, Ralph Kay, a citizen of the United States of America, residing in New York city, in the Borough of Manhattan, county and State of New York, have invented a new, original, and ornamental Design for a Slide Fastener Closure, of which the following is a specification, reference being had to the accompanying drawing, forming part thereof, wherein

The characteristic feature of my design resides in the combination on the slide fastener closure disclosed, of the cartridge tucks alternated with beads, as shown.

I claim:

The ornamental design for a slide fastener closure, substantially as shown and described.

RALPH KAY.
